W. A. Royce,
Pneumatic Apparatus,
No 17,394, Patented May 26, 1857.

UNITED STATES PATENT OFFICE.

WILLIAM A. ROYCE, OF NEWBURGH, NEW YORK.

MACHINERY FOR COMPRESSING GASEOUS BODIES.

Specification forming part of Letters Patent No. 17,394, dated May 26, 1857; Reissued December 24, 1872, Nos. 5,201 and 5,202.

To all whom it may concern:

Be it known that I, WILLIAM A. ROYCE of the town of Newburgh, in the county of Orange and State of New York, have made 5 a new, novel, and useful Improvement in the Construction of Pneumatic Condensers, Reservoirs, and Conduits; and I hereby declare the following to be a full, clear, and exact description of the same, reference being had 10 to the accompanying drawings, which drawings are lettered to correspond with and form a part of the specification.

Description: In order that the public may fully understand my invention, and those 15 skilled in the art, be enabled to construct and operate the same, I will describe it as follows.

Figure 1 represents a vertical section of my pneumatic cylinder or condenser (A.) 20 Letter (a) is a hollow piston-rod that connects with the double convex hollow piston. (b b) has a core (c) in its center with sufficient space between the upper and lower head (or half) of the piston and the said 25 core to allow any fluid that passes up through the lower piston rod (a') into the lower section of the hollow piston to pass around the core (c) up into the piston rod (a) from whence it is discharged through 30 the small holes (d, d,) in the upper end of the piston rod after having performed the office of cooling the piston and rod. The piston is bolted together through the core as shown at Figs. 1, 2, 3. Letters (e, e, e, e,) 35 are ingress and egress valves that communicate with the refrigerating pipe (f, f', f'', f''' f''') through which the compressed aeriform body from either end of the cylinder is driven by the movement of the piston 40 (b, b.) The great amount of heat evolved by compression of elastic fluids is more or less dissipated by my refrigerating pipe (or tube). A great amount of heat if desired may be absorbed by the liquid surrounding 45 the metallic cylinder (A' A'') and the metallic tube (f, f', f'', f''' f''') the whole apparatus being submerged in the liquid. In the lower end of the piston rod (a, a') there is a valve opening upward which admits the liquid to pass up into the piston rod when it is forced down as represented 50 at (h). The necessary stuffing boxes at the upper and lower head of each cylinder is shown at (i, i). At the lower end of the

metallic cylinder there is a pump barrel connected with the stuffing box (i, i) through which the piston rod (a, a') traverses thus forming a force pump by means of which a current of fluid is circulated through the hollow double convex piston and rod for the 60 purpose as above set forth. The metallic cylinder heads are concave, convex and fitted in order to work so close in the extreme stroke of the piston as to displace almost totally the contents of the cylinder 65 whether liquid or aeriform. Spray injections may be used to counteract the heat evolved by compression instead of the refrigerating pipe and hollow piston as above described and shown in the drawings, to effect 70 this a number of internal perforations through the cylinder heads to distribute the stream from a force pump or fountain is all that is necessary. Any ordinary power may be applied to operate the pump by means of 75 the crank as shown at (j, j', j'') in the drawings, or otherwise.

Figs. (2 and 3) represent a pair of cylinders similar in construction to Fig. (1) and arranged upon a metallic bed plate for 80 operating. The cylinders (A) and (A) are of different capacity and work simultaneously, the larger discharging into the lesser cylinder. Any number of these cylinders may be arranged and operated after 85 the above plan (by discharging larger into lesser) preserving the same principle of economy in force used to attain an elastic power in conduits or reservoirs, and at the same time bearing in mind to expose the 90 compressed matter to the refrigerating process as condensation progresses.

Fig. (4) is a reservoir for holding compressed air or other gaseous bodies and is provided with a safety valve stop cocks, &c., 95 by which its contents can be drawn off for use. The reservoirs and tubes are coated on the inside with close grained metal, vegetable gums, resins, oils, or extracts to prevent the escape of the gaseous bodies 100 through the pores of the investing metal.

The object of my pneumatic apparatus is to charge or fill reservoirs or conduits with compressed aeriform bodies by means of some known mechanical power. The force 105 pumps (A', A'') refrigerating pipes (f f' f'' f''' f''') and main reservoir are stationary as shown in the drawings and the com-

pressed gaseous media are transferred from the force pump or pumps or main pipes or this fixed main reservoir by means of pipes stop cocks, &c.

5. What I claim as my invention and desire to secure by Letters Patent of the United States is—

The above described apparatus for compressing or packing gaseous media substan-

tially as described and shown in the drawings.

In testimony whereof I hereunto subscribe my name in the presence of two witnesses.

W. A. ROYCE.
